GUIDE MEANS FOR WOOD SHAPERS

Clarence H. Kemmerer, Emmaus, Pa.

Application April 5, 1951, Serial No. 219,469

5 Claims. (Cl. 144—134)

1

This invention relates to guide means for wood shapers.

An object of the present invention is to provide a guide means for wood shapers which has an effective work guiding width such as to enable a work piece to be subjected to any desired shaping operations.

Another object of the present invention is to provide a guide means for wood shapers which is adapted for securement to a work table and the housing of a portable wood shaper when the latter named housing is attached to the work table in such manner that its rotatable cutter shaft extends horizontally over the work table in substantial parallelism with the latter.

A further object of the present invention is to provide a guide means for a portable wood shaper which is simple in structure, highly efficient in action, and commercially feasible.

Other objects and features of novelty will be apparent from the description taken in conjunction with the drawings in which

Figure 1 is a perspective view of the guide means of the present invention applied to a work table and the housing of a portable wood shaper.

Figure 2 is an exploded view of the guide means shown in Figure 1.

Figure 3 is an end view of the right hand guide element of the guide means shown in Figure 2, viewed from the left of such element.

Figure 4 is a perspective view of another form of the guide means of the present invention applied to a work table and the housing of a portable wood shaper.

Figure 5 is an end view of the left hand guide element of the guide means shown in Figure 4, viewed from the left of such element.

Figure 6 is a sectional view taken on the line 6—6 of Figure 5.

Referring to Figures 1 to 3 of the drawings, the numeral 10 designates a work table to which is secured the housing 11 of a portable wood shaper 12. A rotatable cutter shaft 13 extends horizontally from the housing 11 over the work table 10 in substantial parallelism with the upper surface of the work table, the shaft 13 carrying a cutter 14 inwardly of one end thereof. Complemental spaced guide elements 15 and 16 arranged in aligned relation are secured respectively to the work table 10 and the wood shaper housing 11. The guide element 15 takes the form of an upstanding bar and is provided with a slot 17 extending inwardly from the end face facing the guide element 16 intermediate the top and bottom thereof for the accommodation of the one end of the wood shaper shaft 13. The guide element 15

2

above the slot 17 is cut away at an angle to provide a downwardly sloping end face portion 18. Fixedly superimposed upon the sloping end face portion 18 of the guide element 15 is a plate 19 having a rounded face, the plate extending from the bottom edge of the portion 18 toward and spaced from the top edge of such portion. The complemental guide element 16 takes the form of an upstanding bar and is likewise cut away at 10 an angle to provide a downwardly sloping end face portion 20, and on such end face portion is also fixedly superimposed a plate 21, the plate extending from the bottom edge of the portion 20 toward and spaced from the top edge of such portion. The sloping end face portions 18 and 20 of the guide elements 15 and 16 respectively form together a trough shaped guideway for guiding a work piece over the cutter 14 and transversely of the cutter shaft 13. It is to be noted 15 that the complemental guide elements 15 and 16 have an effective work guiding width which is at least as great as the diameter of the cutter shaft 13 and not greater than the width of the shaper housing 11.

20 In the form of Figures 4 to 6 inclusive, the guide means comprises complemental guide elements 30 and 31 arranged in aligned spaced relation which are secured respectively to the work table 10 and the wood shaper housing 11. The guide element 30 takes the form of an inverted U-shaped member or hood which is slidably and adjustably secured to an upstanding inverted U-shaped support 33 fixedly carried by the work table 10 by means of a threaded bolt 34 extending through 25 the hood and support and a wing nut 32 in threaded engagement with the free end of the bolt 34. The one end of the wood shaper shaft 13 extends into the guide element or hood 30. It is to be noted that the support 33 is adjustably secured to the work table 10 by means of bolts 35 extending through the base of the support and the adjacent portion of the work table. The guide element 31 takes the form of an upstanding bar, the end of such bar which faces the guide element 30 having a projecting abutment 36. The complemental guide elements 30 and 31 likewise have an effective work guiding width which is at least as great as the diameter of the cutter shaft 13 and not greater than the width of the shaper housing 11.

30 Referring to Figures 1 to 3 of the drawings, the numeral 10 designates a work table to which is secured the housing 11 of a portable wood shaper 12. A rotatable cutter shaft 13 extends horizontally from the housing 11 over the work table 10 in substantial parallelism with the upper surface of the work table, the shaft 13 carrying a cutter 14 inwardly of one end thereof. Complemental spaced guide elements 15 and 16 arranged in aligned relation are secured respectively to the work table 10 and the wood shaper housing 11. The guide element 15 takes the form of an upstanding bar and is provided with a slot 17 extending inwardly from the end face facing the guide element 16 intermediate the top and bottom thereof for the accommodation of the one end of the wood shaper shaft 13. The guide element 15

35 In operation of the form of the guide means of Figures 1 to 3, a work piece in the form of a table leg is placed transversely within the trough guideway formed by the cooperating sloping end face portions 18 and 20 of the guide elements 15 and 16 and over the cutter shaft 13 with the adjacent

portions of the table leg bearing against the rounded faces of the plates 19 and 21 on the sloping end face portions 18 and 20 and the ends of the table leg spaced from the bounding edges of the trough guideway. With the table leg thus positioned, the operator then urges the leg into and out of engagement with the cutter 14 while reciprocating the leg in the trough guideway. By these operations it is possible to effect rounding and chamfering of portions of the table leg in either straight or curved paths.

For use of the form of the guide means of Figures 4 to 6, a work piece in the form of a table leg with the leg having a flat surface along a portion of its length is placed transversely of the guide elements 30 and 31 and over the cutter shaft 13 with the flat surface of the table leg abutting against the abutment 36. With the table leg thus positioned, the operator then urges the portion of the leg opposite its flat surface into and out of engagement with the cutter 14 while reciprocating the table leg between the guide elements 30 and 31. By these operations it is possible to effect rounding and chamfering of portions of the table leg other than the flat surface portion in either straight or curved paths.

Having thus described the invention what is claimed as new and desired to be secured by Letters Patent is:

1. The combination with a work table and a portable type wood shaper having a housing arranged so that the housing is perpendicular to the edge of the work table and secured to the work table, a rotatable cutter shaft extending horizontally from the housing over the work table in substantial parallelism with the upper surface of the work table, and a cutter on said cutter shaft, of means for guiding a work piece over said cutter transversely of the cutter shaft comprising two complemental guide elements secured respectively to the top of the work table and to the upper part of the housing of the wood shaper and having an effective work guiding width at least as great as the diameter of the cutter shaft and not greater than the width of the shaper housing, said guide elements extending generally longitudinally of said cutter shaft and in longitudinal alignment with respect to each other.

2. The combination with a work table and a portable type wood shaper having a housing arranged so that the housing is perpendicular to the edge of the work table and secured to the work table, a rotatable cutter shaft extending horizontally from the housing over the work table in substantial parallelism with the upper surface of the work table, and a cutter on said cutter shaft, of means for guiding a work piece over said cutter transversely of the cutter shaft comprising two complemental guide elements secured respectively to the top of the work table and to the upper part of the housing of the wood shaper and having an effective work guiding width at least as great as the diameter of the cutter shaft and not greater than the width of the shaper housing, said guide elements extending generally longitudinally of said cutter shaft and in longitudinal alignment with respect to each other, the confronting end faces of said elements sloping downwardly from the top thereof and together forming a trough guideway.

3. The combination with a work table and a portable type wood shaper having a housing arranged so that the housing is perpendicular to the edge of the work table and secured to the work table, a rotatable cutter shaft extending

horizontally from the housing over the work table in substantial parallelism with the upper surface of the work table, and a cutter on said cutter shaft, of means for guiding a work piece over said cutter transversely of the cutter shaft comprising two complemental guide elements secured respectively to the top of the work table and to the upper part of the housing of the wood shaper and having an effective work guiding width at least as great as the diameter of the cutter shaft and not greater than the width of the shaper housing, said guide elements extending generally longitudinally of said cutter shaft and in longitudinal alignment with respect to each other, the confronting end faces of said elements sloping downwardly from the top thereof and together forming a trough guideway, and opposed plates on the sloping end faces of said elements, each of said plates having a rounded surface.

20 4. The combination with a work table and a portable type wood shaper having a housing arranged so that the housing is perpendicular to the edge of the work table and secured to the work table, a rotatable cutter shaft extending horizontally from the housing over the work table in substantial parallelism with the upper surface of the work table, and a cutter on said cutter shaft, of means for guiding a work piece over said cutter transversely of the cutter shaft comprising two complemental guide elements secured respectively to the top of the work table and to the upper part of the housing of the wood shaper and having an effective work guiding width at least as great as the diameter of the cutter shaft and not greater than the width of the shaper housing, said guide elements extending generally longitudinally of said cutter shaft and in longitudinal alignment with respect to each other, the guiding element on the work table being adjustable relative to the guiding element on the shaper housing.

5. The combination with a work table and a portable type wood shaper having a housing arranged so that the housing is perpendicular to the edge of the work table and secured to the work table, a rotatable cutter shaft extending horizontally from the housing over the work table in substantial parallelism with the upper surface of the work table, and a cutter on said cutter shaft, of means for guiding a work piece over said cutter transversely of the cutter shaft comprising two complemental guide elements secured respectively to the top of the work table and to the upper part of the housing of the wood shaper and having an effective work guiding width at least as great as the diameter of the cutter shaft and not greater than the width of the shaper housing, said guide elements extending generally longitudinally of said cutter shaft and in longitudinal alignment with respect to each other, the guiding element on the shaper housing having a projecting abutment on its end face confronting the guiding element on the work table.
